[57] CLAIM

The ornamental design for a bottle, substantially as shown and described.

DESCRIPTION

FIG. 1 is a front view in elevation of a bottle showing my new design, the obverse view being identical to the front view;

FIG. 2 is an end view in elevation thereof, both end views being identical;

FIG. 3 is a top plan view;

FIG. 4 is a bottom plan view; and

FIG. 5 is a fragmentary sectional view taken on the line 5—5 of FIG. 1.
